(57) **CLAIM**

We claim the ornamental design for a terminal block of a battery pack, as shown and described.

DESCRIPTION

FIG. 1 is a front perspective view of a first embodiment of a terminal block of a battery pack, showing our new design. FIG. 2 is a rear perspective view of the terminal block of the battery pack shown in FIG. 1.

FIG. 3 is another rear perspective view of the terminal block of the battery pack shown in FIG. 1.

FIG. 4 is a first side view of the terminal block of the battery pack shown in FIG. 1.

FIG. 5 is a second side view of the terminal block of the battery pack shown in FIG. 1.

FIG. 6 is a rear view of the terminal block of the battery pack shown in FIG. 1.

FIG. 7 is a top view of the terminal block of the battery pack shown in FIG. 1.

FIG. 8 is a front perspective view of a second embodiment of a terminal block of a battery pack, showing our new design.

FIG. 9 is a rear perspective view of the terminal block of the battery pack shown in FIG. 8.

FIG. 10 is another rear perspective view of the terminal block of the battery pack shown in FIG. 8.

FIG. 11 is a first side view of the terminal block of the battery pack shown in FIG. 8.

FIG. 12 is a second side view of the terminal block of the battery pack shown in FIG. 8.

FIG. 13 is a rear view of the terminal block of the battery pack shown in FIG. 8; and,

FIG. 14 is a top view of the terminal block of the battery pack shown in FIG. 8.

The broken lines represent unclaimed subject matter and form no part of the claimed design. The dash-dot broken lines represent boundary lines. The dash-dot broken lines themselves form no part of the claimed design.
